UNITED STATES PATENT OFFICE.

FRANK R. JOHNSON, OF NEW YORK, N. Y.

LONGITUDINAL RAILROAD-RAIL HOLDER.

SPECIFICATION forming part of Letters Patent No. 437,302, dated September 30, 1890.

Application filed May 21, 1890. Serial No. 352,683. (No model.)

To all whom it may concern:

Be it known that I, FRANK R. JOHNSON, a citizen of the United States, residing in the city, county, and State of New York, have invented a new and useful Longitudinal Rail-Holding Fish-Plate for Railroads, of which the following is a specification.

Heretofore it has been the practice to provide notches in the base of fish-plates and 10 drive spikes within these notches into the ties to prevent the rails from longitudinal displacement; but it is shown by extensive experience that this does not accomplish the desired result, for the reason that the spikes 15 do not engage the ties to the fish-plate with sufficient security, the spikes being torn from the ties by the longitudinal strain of the rails.

The object of my invention relates to providing a fish-plate so peculiarly formed as to 20 serve the double purpose of splicing the ends of the rails together and of preventing the rails from moving in a longitudinal direction, known as the "creeping" of rails, as also to 25 provide greater stiffness and strength to the fish-plate; and the nature of my invention consists in forming the two opposite corresponding parts of the fish-plate in such a way 30 that they (the fish-plates) will engage two or three (as may be preferable) cross-ties of the road in such a manner that the rails cannot longitudinally move without carrying the engaged ties with them.

Figure 1 is a perspective view, including 35 the ends of two rails and a portion of two ties; Fig. 2, a longitudinal elevation, including the ends of two rails and cross-section of two ties, and showing one half of the device as applied to the rails and ties, the other half being the same as the half shown; Fig. 3, a cross- 40 section, seen on the line $x-x$ of Fig. 2 as applied to the rails and ties; Fig. 4, a longitudinal elevation, same as Fig. 2, only that the device is extended in length to engage 45 with three instead of two ties, which on heavy roads is sometimes preferable.

Similar letters refer to similar parts throughout the several views.

A A represent cross-sections of ties (metallic ties, as shown); B B, the end portions of 50 two rails; w w, the web portions of the rails; C C, Fig. 3, a pair of the fish-plates; c' c', the

horizontal or base portion of the fish-plate; c'' c'', the downwardly-projecting portion or lip of the fish-plate, being cut away or bifurcated opposite to the ties A A to engage the 55 ties by striding them and to allow them (the ties) to come in contact with the rail.

e and e' are bolts and nuts that clamp the two opposite halves of the fish-plates to the rails between the head and base thereof; d' d' 60 and a a, bolts and nuts which bind the clips D D to the rails and ties. It will be seen that the slanting or horizontal portion of the fish-plate is sufficiently cut away to afford room for the nose of the clips D D. 65

The lip or downwardly-projecting portion of the fish-plates c'' c'' is cut away or bifurcated equal to the width of the ties, so as to stride and engage them, as clearly shown in Figs. 1, 2, and 4. This lip of the fish-plate 70 extends vertically down about half the depth of the ties, in order to securely engage therewith.

Having sufficiently described my invention to give a clear understanding of its several 75 parts and their respective functions, I will now briefly explain its operation.

It will be seen that when the two opposite halves of the fish-plates are firmly bolted to the rails and their downwardly-projecting lips 80 engage the two (or it may be three) ties it will be impossible for the rails to take any longitudinal movement without breaking the clamping-bolts e e', or carrying the ties with them, which are straddled and engaged by 85 the fish-plates. It will be seen that both fish-plates—that is, the two standing opposite each other—stride and engage the same ties, by which the ties are doubly secured to the fish-plates. 90

I am aware of the English patent, No. 3,704, of 1867, in which is provided a rail in two parts, or a double rail—a base-rail and head-rail—the character of their union being of the tongue-and-groove order, one of which rails 95 breaks joints with the other, in connection with which no fish-plate whatever is used; but in this English patent I am aware there is employed a peculiar device which is bolted to the rail and protrudes into the tie, but not 100 at all in the form or manner of a fish-plate, or at all in the form or manner of my device.

herein set forth. While this device in the said English patent may prevent the longitudinal displacement of the described double rail, it does not act as a fish-plate, as the inventor particularly disclaims the use of such plates altogether as one of the merits of his invention.

What I claim as new and useful, and desire to secure by Letters Patent, is—

- 10 In connection with railroads, the fish-plate C C, having the downwardly-extending lips c'' c'' and cut away or bifurcated at intervals to

engage the ties, in combination with the T-rails B B and ties A A, whereby the device accomplishes the double purpose of securing 15 the ends of the rails in line with each other and preventing their longitudinal movement, substantially in the manner and for the purpose described.

FRANK R. JOHNSON.
